[57] **CLAIM**

The ornamental design for a combined window and frame, as shown and described.

DESCRIPTION

FIG. 1 is a front perspective view of a combined window and frame of the present invention;

FIG. 2 is a rear elevational view of the window with frame of FIG. 1;

FIG. 3 is a right side elevational view of the window with frame of FIG. 2;

FIG. 4 is a left side elevational view of the window with frame of FIG. 2;

FIG. 5 is a top elevational view of the window with frame of FIG. 1;

FIG. 6 is a bottom elevational view of the window with frame of FIG. 1; and,

FIG. 7 is a front perspective view of the combined window and frame of FIG. 1, the broken lines showing a vehicle are for illustrative purposes only and form no part of the claimed design.

FIG. 1

FIG. 5

FIG. 6

FIG. 3

FIG. 4

FIG. 2

FIG. 7
